UNITED STATES PATENT OFFICE.

CLARENCE T. MAPES, OF CRAFTON, PENNSYLVANIA, ASSIGNOR TO OIL WELL SUPPLY COMPANY, OF PITTSBURGH, PENNSYLVANIA, A CORPORATION OF PENNSYLVANIA.

CASING-SPEAR.

1,262,367.

Specification of Letters Patent. Patented Apr. 9, 1918.

Application filed December 13, 1915. Serial No. 66,416.

To all whom it may concern:

Be it known that I, CLARENCE T. MAPES, a citizen of the United States, and resident of Crafton, in the county of Allegheny and 5 State of Pennsylvania, have invented certain new and useful Improvements in Casting-Spears, of which the following is a specification.

The object of this invention is to provide 10 a spear of improved construction for removing the casing from oil, gas and other wells, wherein the slips are so arranged as to prevent deforming the casing under the great strain incident to maintaining a gripping hold. This feature of the invention is 15 embodied in a plurality of slips which encircle the body and which coöperate with the slip-expanding portion of the latter in such manner that substantially all portions 20 of the casing interior in the plane of the slips are subjected to the same gripping action.

A further object is to provide automatically trippable slip-supporting means of improved construction for maintaining the slips in different set positions as may be required for different sizes or weights of casing. Still a further object is to provide improved means for maintaining the slips in 30 position on the body without retarding the operation of the slip-supporting means.

In the accompanying drawings, Figure 1 is a side elevation of a spear constructed in accordance with the invention, showing the 35 appliances applied thereto for setting the same. Fig. 2 is a vertical section of the spear in set position as when being lowered in a well casing, and Fig. 3 is a similar view illustrating the position of the parts 40 after the spear has been tripped and its hold on the casing relaxed for removing it from the casing either after the latter has been pulled from the well, or if the casing is too tightly held to be removed by the 45 spear. Figs. 4 and 5 are sectional plan views taken on lines 4—4 and 5—5, respectively, of Fig. 2. Fig. 6 is a vertical section of the lower portion of the spear illustrating a modified arrangement of trip support and support holding latches. Fig. 7 50 is a sectional plan on line 7—7 of Fig. 6.

Referring to the drawings, the upper portion of spear body 2 is of conventional well-tool form, being provided with the usual

wrench hold 3 and coupling pin 4 for connecting with the tools for lowering and raising the spear. Beneath the wrench hold the body is formed with the upwardly tapering slipway 6, which is circular in cross-section and at its upper end terminates in the undercut shoulder 7. Beneath slipway 6 the body is of reduced diameter to form stem 8 with its lower extremity threaded at 8' to receive the rounded and tapered nut-forming head 9, the bore of which above its threaded formation is larger than stem 8, as indicated at 9', to provide a seat for the lower portion of a stout coiled spring 10. Encircling and movable vertically on stem 8 is collar 11 having its under side recessed 70 at 11' to receive the upper end of the spring. When fully elevated as in Fig. 3 collar 11 is adapted to engage shoulder 12 formed by the lower extremity of slipway 6.

Collar 11 comprises a support for a plurality of segmental slips 13, the latter resting thereon and slidable vertically on slipway 6 and with their inner faces curved to fit the slipway and their outer surfaces formed with serrations 13' usual in this 80 class of devices for obtaining a biting hold on the casing. The slips are of downwardly tapering form so that while their inner surfaces are in engagement with slipway 6 their outer faces are disposed substantially 85 vertical. The upper extremities of the slips are inclined downwardly and outwardly as indicated at 7' to conform with the undercut shoulder 7, whereby when the slips are fully elevated as in Fig. 3 their upper extremities are in a sense pocketed and thus held against outward movement. Similarly, the top face of collar 11 and the bottom extremity of the slips are so beveled that the latter are held contracted when elevated, 90 this irrespective of spring ring 14. As will be seen from Fig. 3, the cavity or pocket 7 and face of collar 11 form what may be considered as housing members for the slips when the latter are contracted. This is of 100 advantage during withdrawal of the spear, in that swaying of the latter within the casing and contact of slips with the casing would be ineffective to move the slips outwardly to disarrange the housed relation. 105 This also permits the use of slips free from interlocking engagement with the slipway, greatly decreasing the cost of manufacture

through elimination of the expensive machining operations, and also reduces liability of the slips sticking.

A split spring metal ring 14 embraces the 5 several slips, being confined in a groove formed therein, holding them contracted on slipway 6, without, however, interfering with their vertical movement, ring 14 not being sufficiently strong to sustain the 10 weight of the slips although holding them contracted, whereby the slips will move with collar 11 either upwardly or downwardly as the case may be.

Four segmental slips are preferably employed as shown in Fig. 4 with the slips of 15 each pair in opposed relation at diametrically opposite sides of slipway 6. While the invention is not limited as to the number of slips, when two pairs are used the slips 20 of each pair operate in such opposed manner that substantially all portions of the casing within the range of the slips is subjected to equal strain when the spear has 25 been set and the pulling force applied. With the slips and slipway constructed and arranged as shown, the former may rotate on the latter, thereby, in addition to other advantages, subjecting the engaging surfaces to uniform wear. Also, such formation 30 facilitates the forming operations, the slipway being shaped by turning and the inner faces of the slips by boring, a circular slip blank being sawed into four segments after it has 35 been provided with the desired bore, also after turning up the biting serrations on its outer surface.

In the adaptation shown in Figs. 1 to 5, collar 11 is provided with two pairs of 40 latches or latch bolts 15 confined in openings therein by perforated plugs 16, a spring 17 being arranged to hold each latch normally 45 in outwardly projecting position. The inner extremity of each latch is notched at 18 whereby each pair of opposed latches is 50 adapted to engage the undercut groove 19 in stem 8, thereby holding collar 11 depressed and the slips in lowered and set 55 position as in Figs. 1 and 2. One pair of latches 15 is arranged slightly above the other pair, whereby the spear may be set 60 for gripping different weights of casing, the lowermost pair being utilized, as in Fig. 2, for holding the slips in position to grip the heavier or thicker casing, while the upper- 65 most latches are utilized for holding collar 11 lowered and the slips expanded somewhat more as required for the lighter or thinner casing.

For setting the spear, a bar 20, Fig. 1, 70 may be removably connected to collar 11 by arms 21 provided with pins 22 to engage sockets 23 in collar 11. A screw 24 in bar 20 is adapted to engage the lower extremity 75 of head 9, whereby upon rotating the screw 65 the collar is depressed and spring 10 con-

tracted until the desired latches to be set are opposite stem groove 19, whereupon the latches may be projected inwardly by suitable push devices, eye-pins 25 being usually employed for the purpose which are entered 70 through the latch-confining plugs 16. With the latches pressed inwardly in opposition to their springs 17 and with their undercut extremities 18 entered in groove 19, the hold of screw 24 is relaxed and the 75 latches operate to hold collar 11 in the desired position. Upon removing the setting mechanism, the spear is in condition to be lowered in the casing as in Fig. 2 and so long as the downward movement is 80 continued there is no operation of the parts, the slips sliding downwardly on the inner face of the casing, being thereby slightly raised from collar 11. Having been lowered to the point where it is desired to grip the 85 casing, the movement is reversed and immediately upon lifting the spear they impinge the casing with a biting hold, and the ensuing relative upward movement of the spear body relaxes the hold of latches 15 and the 90 latter spring outwardly into the released position as in Fig. 3. Further upward movement of the spear body causes slips 13 to obtain uniform hold on all portions of the casing within their range and the 95 casing is withdrawn unless the resistance encountered is too great for the spear or the operating line. If too great, the hold of the spear is released by simply lowering its body, whereupon the hold of slips 13 is relaxed 100 and immediately spring 10 operates to raise the collar and slips into the contracted and inoperative position shown in Fig. 3 when the tool may be entirely withdrawn. The same procedure is had when releasing the 105 slips from the casing after the latter has been removed from the well.

In the embodiment shown in Figs. 6 and 7 collar 11 is non-rotatably secured to stem 8 by spline 26. The several latches 15 are 110 arranged in the same plane instead of pairs thereof in different planes as in the first described adaptation, and stem 8 is formed with two pairs of depressions 27 with pairs 115 in different vertical planes. By this means the collar may be set at different elevations as will be understood, depending on the weight of the casing.

I claim:

1. In a casing spear, the combination of a 120 body having its exterior formed to receive a plurality of slips, slips in engagement with such body formation, the engaging surfaces of the body and slips arranged to expand the slips when the body moves upwardly 125 relatively thereto, a contractile spring encircling the slips and holding them in engagement with the body and operating to contract the slips on the body when the latter moves downwardly relatively thereto, the 130

resilient holding means having such relation to the weight of the slips as to be ineffective to prevent the slips from lowering by gravity, vertically movable spring-raised slip supporting means mounted on the body and adapted when released from depressed position to elevate the slips, and trippable means for holding the supporting means depressed, said body and slip-supporting means being adapted to coöperate with said slips to retain them housed when moving the spear relatively to the casing.

2. In a casing spear, a body portion having a slipway and having a slip-receiving cavity at one end of the slipway, a spring-sustained member movable axially of the body beyond the opposite end of the slipway, a plurality of slips mounted on and movable axially of the slipway with slips and slipway complementally formed to provide slip expansion and contraction by movements of the slips relative to the slipway, said spring-sustained member having a configuration adapted to act as a housing element for the slips when the latter are located within the body cavity, and means for releasably holding said member in position to permit free movements of the slips on the slipway to expand the slips, the member

when released adapted to move the slips to housed position.

3. In a casing spear, a body portion having a slipway and having a slip-receiving cavity at one end of the slipway, a spring-sustained member movable axially of the body beyond the opposite end of the slipway, a plurality of slips mounted on and movable axially of the slipway with slips and slipway complementally formed to provide slip expansion and contraction by movements of the slips relative to the slipway, said spring-sustained member having a configuration adapted to act as a housing element for the slips when the latter are located within the body cavity, means for releasably holding said member in position to permit free movements of the slips on the slipway to expand the slips, the member when released adapted to move the slips to housed position, and resilient means for maintaining the slips in contact with the slipway.

In testimony whereof I affix my signature in presence of two witnesses.
